FLOORING STRUCTURE

Otis W. Hovey, Philadelphia, Pa., assignor to Edward G. Budd Manufacturing Company, Philadelphia, Pa., a corporation of Pennsylvania

Application January 13, 1933, Serial No. 651,554

10 Claims. (Cl. 72—64)

The invention relates to flooring structures and particularly to flooring structures for bridges or the like.

Such flooring is required to take heavy wheel loads concentrated at a small area and to distribute such loads over a larger area without injuriously deflecting the flooring. Such wheel loads may reach as high as 20,000 lbs., and impact loads may reach double that value.

10 Heretofore such flooring has usually consisted of thick and correspondingly heavy concrete slabs, which added very substantially to the weight of the bridge or like structure, and in such structures of long span, as for example, the George Washington bridge over the Hudson River, since the weight of the remaining bridge structure is many times the weight of the flooring, i. e., one pound of flooring necessitating many pounds of structures to support it, the use of such heavy flooring adds very materially to the expense of the bridge structure as a whole, even though the flooring itself is relatively inexpensive.

It is an object of the invention to provide a floor structure which is relatively light in weight as compared with known such structures, a structure that is easy of manufacture and one that is very effective in distributing the concentrated loads over the adjoining areas and into the framing supporting the floor.

30 These objects are attained in large measure by constructing the flooring out of metallic members wherever possible out of high tensile stainless steel, which not only is free from corrosion and does not require frequent painting, but is very strong, although of light weight, particularly if given an appropriate section. The metallic members are so coordinated and connected as to give to the resulting flooring structure a very high strength-weight ratio. To this end, there are provided vertical web members of a depth commensurate with the strength required and are arranged in spaced relation at intervals again depending upon the load to be carried, these web members being either flat strips or being provided with widened base portions and interconnected at a point substantially above their base portions by means forming a bottom for the filler and above said connecting means by transverse tie members which form with the tops of the webs with which they are flush, a grating adapted to form wear surfaces, along with filling in the spaces between the web members. Such a metallic structure is very strong, while light in weight, and requires a relatively small amount of filling

5 to complete the roadway surface, and, since the filler forms a very large percentage of the weight in such structures, as heretofore proposed, another decided saving of weight is effected by the present construction.

Other and further objects and advantages and the manner in which they are attained will become apparent from the following detailed description when read in connection with the accompanying drawings, in which,

10 Figures 1 and 2 are respectively, a sectional elevation and a sectional plan of one form of the improved flooring according to the invention.

Figure 3 is a detail sectional view taken on the line 3—3 of Figure 1.

15 Figures 4 and 5 are, respectively, a plan (with parts of the filling broken away), and a sectional view of a modified form of flooring.

Figure 6 is a sectional view of a further modification, and

20 Figure 7 is a detail sectional view taken along the lines 7—7 of Figure 6.

According to the form of the invention shown in Figures 1 to 3, the spaced bars 10 are in the form of strip stock preferably of high tensile stainless steel and are of a substantial vertical depth and spaced apart a distance adapting them to carry the loading desired. These bases are, in this instance, widened and strengthened by spot welding to the opposite sides thereof channel section members 11, which may be of lighter gauge, and also preferably of high tensile stainless steel.

25 The bottoms of the bars 10 and the lower side walls of the channels 11 are adapted to rest upon the floor supporting framing, such as the transverse beams 13 also preferably constructed of light gauge stainless steel and of closed box section, flanged laterally at their edges as 14. These beams are suitably spaced to take the desired load. The flooring proper is readily secured 30 to them as by spot welding the bottom side walls of the channel to the flanges 14 of the beams.

35 By this construction the strength of the flooring may be increased by deepening the beams 10, and by interconnecting them adjacent their lower ends, as by a transverse connection, such as a hollow section light gauge steel strip, as heretofore proposed, and instead of resting the flooring structure directly on transverse beams such as 13, the bars 10 may rest directly on longitudinal stringers or other floor supporting framework. It is to be understood, however, that the bars 10 are always to be arranged generally transversely to the frame members directly supporting them.

According to the invention, an important feature is a construction whereby the weight of the concrete or other filler is very materially decreased. To this end the means forming the bottom support for the filler is arranged, not substantially at the base of the bars 10, but a substantial distance above base. In the form shown, the arrangement is substantially at half the height of the bars, but the precise location will vary considerably with the demands of the roadway.

In the form shown, the bars are interconnected transversely at this location by transversely corrugated sheet metal strips secured, as by spot welding, to the top side walls 15 of the channels 11. This corrugated connection provides a very strong connection and is well adapted to take the load transmitted to the filler and transmit it to the bars 10.

Above this bottom partition the bars 10 are strongly interconnected by transverse vertically arranged bar strips 16 forming with the tops of the bars 10 a grating of a fineness adapting it to form the wear surface of the flooring. The spacing of the bars 10 and the transverse interconnecting bars 16 is such as to permit the wheel tread in its engagement with the flooring, to spread over a plurality of the meshes formed by the grating. The grating is preferably formed by having the bars 16 formed with flattened portions 17 where they engage the sides of the bars 10 and diagonal portions 18 extending from bar to bar between adjacent flattened portions engaging adjacent bars. The parts are preferably joined by spot welding through the overlapping portions.

The metallic framework so described is readily fabricated and assembled and forms substantially the entire load sustaining and distributing structure of the flooring. To finish the smooth roadway surface, and where concrete or other filler adapted to take high compression is used to add somewhat to the strength of the structure, the spaces formed by the meshes of the grating are filled flush with the top of the grating with an appropriate filler 19. Appropriate materials for the filler are concrete, asphalt, and other materials capable of flowing when applied and of subsequent setting and adhering to the metallic framework and withstanding the elements. The filler may also be interlocked vertically with the grating by flowing under the grating bars 16.

According to the modification shown in Figure 5 the entire metallic framework comprising the flooring proper excluding the transverse connecting members 16 of the top grating, may be made of integral beams of relatively inexpensive rolled stock.

This stock may comprise a deep vertical web portion 20, a widened base portion 21, laterally extending portions 22 projecting from the web portion and arranged a substantial distance above the base portion, in the instance shown, nearer the top than the base of the web. The lateral extensions 22 of adjacent beams bridge the space between the beams and form the bottom for supporting the filler. Along their adjacent edges, the members 22 may be welded together, or otherwise joined to still further increase the strength of the structure and more evenly distribute the load.

A modification of this structure is shown in Figures 6 and 7, in which the integral extensions 22 of the rolled section members of Figure 5 are replaced by a transverse connection, between

the vertical webs of rolled section inverted T-bars 23, of lighter construction similar to that shown in Figures 1 to 3. In this connection, it is shown as consisting of angle strips 24 spot welded to the webs of the bars 23 and transversely 5 corrugated bridging strips 25 spot welded to one of the arms of the angles. In the constructions shown in all the forms herein, it is understood that the structure can, if desired, be additionally reinforced and strengthened by transversely connecting the base portions of the webs of the parallel flooring bars by light gauge hollow section strips, such for example, as are shown in my co-pending application of equal date herewith.

Other and further modifications and departures from the specific structures herein described may be made without departing from the spirit and scope of the invention as set forth in the claims appended hereto.

What I claim is:

1. A flooring structure comprising a plurality of spaced beams having vertical web portions, metallic means bridging the space between said web portions a substantial distance above the base portions thereof, and transverse tie members connecting said webs above said bridging means.

2. A flooring structure comprising a plurality of spaced beams having vertical web portions, metallic means integral with said webs bridging the space between adjacent beams a substantial 30 distance above their base portions, and transverse tie members interconnecting adjacent web portions above said bridging means and forming with the tops of the webs wear surfaces of the flooring.

3. A flooring structure comprising a plurality of spaced web members of strip stock form, angular members welded to opposite sides of the bases of said members to form a widened reinforced base for the webs and means through 40 which the flooring may be secured to the base for the flooring, transversely corrugated strips bridging the space between adjacent beams and secured thereto through said angular members, and transverse tie members connecting said web 45 members above said bridging strips and forming therewith a grating adapted to form a wear surface.

4. A floor structure comprising a plurality of web members of strip stock form, channel members 50 welded to opposite sides of the base portions of said web members, metallic strips connecting said web members and welded to the tops of said channel members in spaced relation to the bases of said web members, and transverse 55 tie members connecting said web members and arranged above said strips to form with the tops of the web members wear portions of the flooring.

5. A floor structure comprising a plurality of inverted T-section bars having their webs extended vertically and their widened bases adapted to rest on floor supporting beams, angular members welded to the opposite sides of said webs a substantial distance above their base portions, and metallic strips corrugated transversely of 65 the bars secured to said angular members and bridging the space between said webs, and transverse tie bars extending between said webs and adapted to form with the top of said webs, wear surfaces of the flooring.

6. A floor structure comprising a plurality of rolled section bars having vertical web portions adapted to rest on floor supporting beams, and integral lateral arms extending from said web portions a substantial distance above said base 75

portions and in meeting and joined relation, the portions of the webs extending above said arms being interconnected by transverse tie members adapted to form with the tops of the webs, wear surfaces of the flooring.

7. A flooring structure comprising a plurality of rolled section bars having vertical webs, widened base portions adapted to rest upon floor supporting framing, and laterally extending arms spaced a substantial distance from the base portions, the arms from adjacent webs being of an extent adapted to bridge the space between the webs, and transverse tie members connecting the webs above said arms and forming a grating with the tops of the webs adapted to serve as a wear surface, and a filler filling the interstices of said grating above said arms to substantially the level of the top of said grating.

8. A flooring structure comprising a plurality of spaced beams having vertical web portions, metallic means bridging the space between said web portions a substantial distance above the base portions thereof, transverse tie members connecting said webs above said bridging means to form with the webs a grating, and a filler fill-

ing the spaces formed by said grating above said bridging means.

9. A flooring structure comprising a plurality of spaced bars having deep vertical webs, means transversely connecting the base portions of the bars, metallic means bridging the space between said webs a substantial distance above the base portions thereof, transverse tie members connecting said webs above said bridging means to form with the tops of the webs a grating adapted to serve as a wear surface.

10. A flooring structure comprising a plurality of spaced web members of strip stock form, angular members welded to opposite sides of the bases of said members to form a widened reinforced base for the webs and means through which the flooring may be secured to the base for the flooring, transversely corrugated strips bridging the space between adjacent beams and secured thereto, and transverse tie members connecting said web members above said bridging strips and forming therewith a grating adapted to form a wear surface.
